[57] CLAIM

The ornamental design for a cable duct, as shown and described.

DESCRIPTION

FIG. 1 is a top view of the cover portion of a cable duct showing our new design;

FIG. 2 is a front view of the cover portion;

FIG. 3 is a left side view of the cover portion, the right side view being a mirror image thereof;

FIG. 4 is a rear view of the cover portion;

FIG. 5 is a top view of the base portion of a cable duct showing our new design;

FIG. 6 is a front view of the base portion;

FIG. 7 is a left side view of the base portion, the right side view being a mirror image thereof;

FIG. 8 is a rear view of the base portion;

FIG. 9 is a top view of a cable duct with the cover portion attached to the base portion showing our new design;

FIG. 10 is a front view of the assembled cable duct;

FIG. 11 is a left side view of the assembled cable duct, the right side view being a mirror image thereof; and,

FIG. 12 is a rear view of the assembled cable duct.

The front, rear and side views are shown broken away for the purpose of indicating an indeterminate length.
